ALL METAL VALVE WITH PARTICULAR HEAD
AND SEAT CONSTRUCTION

Donald W. Latshaw, Jr., Los Altos, and Russell E. Bostwick, Mountain View, Calif., assignors to Kane Engineering Laboratories, Palo Alto, Calif., a corporation of California

Filed Sept. 13, 1961, Ser. No. 137,852
2 Claims. (Cl. 251—333)

This invention relates to an all metal valve construction and more particularly to an all metal valve construction for use in vacuum systems.

In copending application Serial No. 132,965, filed August 21, 1961, there is disclosed an all metal valve utilizing indium as a seating material. In the use of such a valve, it was found that it was difficult to obtain the required reliability in such a valve because pipes or small passages occurred in the indium upon heating and cooling of the same which made it difficult to obtain a reliable seal. In particular, it was found that these pipes or microscopic passages were formed during initial manufacture of the valve when the valve was raised to a high temperature such as 1100° C. to obtain a wetting of the indium to the stainless steel walls forming the recess for the indium seating material. By actually heating the valve up to such an elevated temperature in a hydrogen furnace, the hydrogen reduces the oxide on the stainless steel to present a pure metal surface to the indium seating material so that a good bond is obtained between the indium and the stainless steel. However, after such a vacuum firing, it was found that these microscopic passages or pipes were formed in the indium seating material which made it difficult to obtain the proper type seal required. In addition to this problem, it was found that some times relatively large contraction cavities would be formed within the indium during cooling of the indium. For example, it was found that one cavity would form at the last spot to solidify in the seating material.

In addition, it was found that the knife edge configuration utilized in the copending application Serial No. 132,965, filed August 21, 1961, also made it difficult to obtain a proper uniform seal because the tapered surfaces of the knife edge portion forced apart the indium seating material so that there was insufficient contact with the knife edge of the valve member. Because of the difficulties, there is need for a new and improved all metal valve.

In general, it is an object of the present invention to provide an all metal valve construction which will overcome the above named difficulties.

Another object of the invention is to provide an all metal valve construction of the above character which utilizes a seating material in which contraction cavities do not form and in which passages or pipes do not form.

Another object of the invention is to provide a valve construction of the above character having a valve member with a seat engaging surface of a particular configuration to obtain a good sealing contact with the seating material.

Another object of the invention is to provide a valve construction of the above character having a particularly novel seating material.

Additional objects and features of the invention will appear from the following description in which the preferred embodiment is set forth in detail in conjunction with the accompanying drawings.

Referring to the drawings:

FIGURE 1 is a cross-sectional view of an all metal valve incorporating our invention.

FIGURE 2 is an enlarged cross-sectional view of the

seating material and the lower extremity of the valve member.

In general, our valve construction consists of a body having a passageway and inlet and outlet ports connected to the passageway. An annular recess is formed in the body and encircles the passageway. A relatively soft metallic seating material having a relatively low melting point is disposed in the recess. A valve member movable into and out of engagement with the seating material is utilized for closing the passageway. The valve member is provided with a depending annular flange which is formed with an annular knife edge-like portion which is adapted to engage the seating material. The knife edge-like portion is formed with concave surfaces on opposite sides of the annular knife edge-like portion extending away from the extremity of the knife edge portion to minimize pushing the seating material away from the extremity of the knife edge as it enters the seating material. A new and improved seating material is utilized and consists of an indium copper alloy in which contraction cavities and microscopic pipes or passageways are not formed.

As shown in the drawing, our valve consists of a valve body 11 which is formed to provide a fluid passageway 12 and with ports 13 and 14 connected to the passageway. The body of the valve is of a conventional T-type construction and is formed of suitable material such as stainless steel. The body 11, as shown, is substantially cylindrical and is provided with a tubular extension 16 which defines the port 14 and a cap 18 provided with a cylindrical extension 19 which defines the port 13. An annular recess 21 is formed in the cap 18 as shown and is positioned in such a manner that the walls defining the inner side of the recess define a portion of the passageway. The inner wall of the recess is formed by an extension of the cylindrical member 19 which has its upper surface provided with an inwardly and upwardly extending taper 22 as shown.

A seating material 23 is disposed within the annular recess 21. It is preferably an indium alloy. By way of example, we found that an alloy consisting of 5% copper and 95% indium works very satisfactorily. However, we found that, if desired, a range of 1% to 10% of copper can be utilized with the remainder being indium.

A valve member 24 is movable into and out of engagement with the seating material 23. As shown, the valve member is substantially cup-shaped and is provided with an annular depending flange 26 which has an annular knife edge-like portion 27 on its lower extremity. The annular knife edge-like portion 27 has its outer and inner surfaces radiused to provide concave surfaces which extend upwardly from the lower extremity of the knife edge-like portion. This radiusing of the inner and outer walls of the valve member gives a somewhat tapered effect. The knife edge-like portion terminates in an annular flat surface 29 parallel to the upper surface of the seating material which is adapted to engage the seating material as shown particularly in FIGURE 2. It will be noted that the width of this annular flat surface 29 is relatively small and much less than the width of the upper surface of the seating material so that there is substantially a knife edge provided on the lower extremity of the valve member.

It has been found that this particular configuration of the knife edge-like portion facilitates the obtaining of consistently good seals with the seating material. For example, in one embodiment of our invention, we have found that an annular flat surface 29 of 7 mils in width for a 1 inch valve operated very satisfactorily. The particular configuration of the radiused surfaces 28 provided on the portion 27 were also found helpful to obtain a

better seal because they minimized the pushing aside of the seating material so that the surface 29 always engaged a substantial amount of seating material.

Means is provided for moving the valve member 24 between open and closed positions and consists of a lead screw 31 threaded into a nut 32. The nut 32 is provided with tool recesses 33 and is affixed to a cap 34 by suitable means such as welding. The cap 34 is affixed to the body 11 of the valve also by suitable means such as welding.

A stem 36 is formed on the lower end of the lead screw 31 and is mounted within a stem seat 37 which is an integral part of the valve member 24. A washer 38 is affixed to the stem seat and engages a groove 39 provided in the stem to mount the valve member on the stem. Means is provided for establishing a vacuum-tight seal between the valve member 24 and the body and consists of a bellows 41 which has its lower extremity in sealing engagement with the valve member 24 and its upper extremity in sealing engagement with the side wall of the body 11 as shown.

A lead screw 31 is provided with a squared portion 42 which is adapted to be engaged by a suitable tool for rotating the lead screw as, for example, a knob 43 which has incorporated in it a conventional slip clutch such as the one built by the Snap-On Tool Corp. As is well known to those skilled in the art, such a knob is adjustable so that upon the application of a predetermined amount of torque, the clutch built into the knob will slip to prevent additional tightening of the valve member 24. As hereinafter described, this prevents running the valve member 24 further down into the seating material than is required to establish a good vacuum seal.

Although other materials may be utilized, we have found it desirable to utilize stainless steel for all the parts of the valve except for the seating material 23.

The cap 18 has such a configuration so that a heater such as that described in copending application Serial No. 132,965, filed August 21, 1961, can be mounted on the cap to melt the seating material 23 to thereby reflow the seating material to remove any indentations which have been placed in the seating material by the valve member 24. Thus, when the valve has been opened and closed a sufficient number of times so that the valve member has been urged substantially through all the seating material, the valve member will engage the extension 19a which serves as a mechanical stop. The seating material should then be reflowed to provide a new seating surface in the valve. However, when this is accomplished, the valve seat should be in a horizontal position so that the seating material will not flow from the recess 21. As explained in the copending application Serial No. 132,965, filed August 21, 1961, this is advantageous because the valve need not be removed for this purpose.

It is apparent from the foregoing that we have provided a new and improved all metal valve with which it is possible to perform a large number of openings and closings of the valve while at the same time obtaining a good vacuum seal each time the valve is closed. The slip clutch

provided controls the depth of penetration of the knife edge into the seating alloy so that a large number of closures can be obtained before the seating material must be reflowed. By way of example, we have found that uniform closing of the valves can be obtained which has a leakage conductance at the seat which is not more than 10^{-14} liters per second. The valve is constructed in such a manner that the conductance of the valve can be easily and smoothly varied between maximum and minimum limits. The construction is such that the valve member can be moved to a full open position to provide full porting and maximum conductance.

We claim:

1. In a valve construction, a body having a passageway and inlet and outlet ports connected to the passageway, an annular recess formed in the body, a relatively soft metallic seating material having a relatively low melting point disposed in the recess, said seating material being an alloy of indium and copper with the copper ranging in percentage from one percent to 10 percent, and a valve member movable into and out of engagement with the seating material for opening and closing said passageway, the member having an annular depending flange formed with an annular knife edge-like portion on the lower extremity of the same adapted to engage the seating material, the knife edge-like portion being formed with only one annular surface lying in a plane substantially parallel to the plane of the seating material and adapted to engage the seating material, said knife edge-like portion also being formed with substantially concave radiused surfaces on the opposite inner and outer sides of the annular knife edge-like portion and extending upwardly and outwardly away from said one annular surface of the knife edge-like portion, the configuration of the knife edge-like portion being such as to minimize the pushing away of the seating material as the knife edge-like portion enters the seating material to thereby obtain a good seating engagement with the seating material.

2. In a valve construction, a body having a passageway and inlet and outlet ports connected to the passageway, an annular recess formed in the body, a relatively soft metallic seating material having a relatively low melting point disposed in the recess formed in the body, said seating material being formed of an alloy of indium and copper with the copper ranging in percentage from one percent to 10 percent, and a valve member movable into and out of engagement with the seat.
